HYDRAZINE DERIVATIVES

Otto Straub, Bottmingen, and Paul Zeller, Neuallischwil, Switzerland, assignors to Hoffmann-La Roche Inc., Nutley, N.J., a corporation of New Jersey
No Drawing. Filed Oct. 27, 1958, Ser. No. 769,553
Claims priority, application Switzerland Oct. 29, 1957

19 Claims. (Cl. 260—404.5)

This invention relates to substituted acid hydrazides of the general formula

wherein R represents a member of the group consisting of aliphatic and cycloaliphatic hydrocarbon radicals, halogeno-, hydroxy-, acyloxy-, alkoxy- and alkylmercapto-substitution products thereof, and acid addition salts of same.

In the above formula R may represent a saturated or unsaturated cycloaliphatic, a saturated or unsaturated, straight-chained or branched aliphatic hydrocarbon radical or one of these radicals carrying halogeno-, hydroxy-, acyloxy-, alkoxy- or alkylmercapto-substituents. Typical radicals represented by R include alkyl groups, such as lower alkyl groups, e.g. methyl, ethyl, propyl, isopropyl, butyl and the like, as well as higher homologous alkyl groups, such as tetradecyl, hexadecyl, heptadecyl and the like; halogeno-substituted alkyl groups, such as chloromethyl, bromomethyl, chloroethyl, chloropropyl and the like; hydroxy-substituted alkyl groups, such as hydroxymethyl, hydroxyethyl, hydroxypropyl and the like; acyloxy substituted alkyl groups such as acetoxymethyl, acetoxypropyl and the like; alkoxy-substituted alkyl groups, such as methoxymethyl, methoxyethyl, ethoxyethyl and the like; alkylmercapto-substituted alkyl groups such as methylmercaptomethyl, methylmercaptoethyl and the like; and cycloalkyl groups, such as cyclopropyl, cyclobutyl, cyclopentyl and cyclohexyl.

The hydrazine derivatives of this invention may be produced by condensing 1,2-diisopropyl-hydrazine or an acid salt thereof, e.g. a hydro-halide, with an acylating agent bearing the appropriate acyl group, e.g. an acyl halide, preferably the chloride, or an acid anhydride. Approximately equimolecular proportions of 1,2-diisopropyl-hydrazine and acylating agent are used in the condensation reaction. If an acyl halide is used as one reactant, the reaction is preferably carried out in an inert solvent, such as benzene, in the presence of a tertiary base, such as pyridine or triethylamine or of an excess of 1,2-diisopropylhydrazine. Acyloxy-substituted acid hydrazide derivatives thus obtained may be hydrolyzed to the corresponding hydroxy-substitution products according to known methods, e.g. by treatment with a methanolic sodium methylate solution.

The compounds of this invention react with inorganic or organic acids to form acid addition salts. Illustrative salts include those formed with mineral acids, e.g. hydrohalides, such as the hydrochloride, the hydrobromide, the hydroiodide, etc.; phosphate, sulfate, nitrate; as well as oxalate, tartrate, ascorbate, citrate and the like. The acid addition salts form also part of this invention.

The compounds of this invention are monoamine oxidase inhibitors, that is, they inhibit the activity of monoamine oxidase which effects the deamination of physio-

2

logical regulators, such as serotonin, tryptamine, epinephrine, etc., and stimulate the central nervous system. They are useful in psychotherapy for relief of disturbed or depressed states. They are also useful for increasing weight in cases where cachexia is present. The acid hydrazide compound or a medicinally acceptable acid addition salt thereof may be administered orally or parenterally in conventional solid or liquid dosage forms, such as tablets, capsules, injectables, etc., comprising therapeutic doses incorporated in a conventional solid or liquid vehicle with or without excipients.

The following examples are illustrative of the invention. All temperatures are stated in degrees centigrade.

Example 1

23.5 g. of acetyl chloride were added dropwise over a period of two hours, at room temperature, with strong stirring and with the exclusion of moisture, to a mixture of 34.8 g. of 1,2-diisopropyl-hydrazine and 400 cc. of absolute pyridine. The mixture was stirred for an additional two hours at about 60°. Most of the pyridine was then distilled off in vacuo and the residue was taken up in 500 cc. of chloroform. The mixture was then shaken with portions of a concentrated aqueous solution containing 22 g. of potassium carbonate. The chloroform layer was separated and dried over sodium sulfate, then concentrated in vacuo. The oily residue was purified by fractionating several times in vacuo. The product, 1-acetyl-1,2-diisopropyl-hydrazine, thus obtained boiled at 88—89°/12 mm.

1-acetyl-1,2-diisopropyl-hydrazine was treated with ethanolic-HCl to obtain 1-acetyl-1,2-diisopropyl-hydrazine hydrochloride. After crystallization from alcohol/ether, the hydrochloride melted at 153—155°.

Example 2

A solution of 24.1 g. of pivaloyl chloride in 100 cc. of absolute benzene was added dropwise, at room temperature and with stirring, to a solution of 25.5 g. of 1,2-diisopropyl-hydrazine in a mixture of 150 cc. of absolute benzene and 150 cc. of absolute pyridine. The mixture was stirred for an additional 2½ hours at 50°. The suspension thus obtained was concentrated in vacuo and the residue taken up in chloroform. The chloroform solution was shaken with a saturated aqueous solution containing 15 g. of potassium carbonate. The chloroform layer was separated, washed with a saturated sodium chloride solution, dried over sodium sulfate and concentrated in vacuo. The oily residue was purified by fractionating several times in vacuo. The colorless product thus obtained, 1-pivaloyl-1,2-diisopropyl-hydrazine, boiled at 89—92°/13 mm.

Example 3

A solution of 27.5 g. of palmitoyl chloride in 100 cc. of absolute benzene was added dropwise, with stirring, to a solution of 32 g. of 1,2-diisopropyl-hydrazine in 150 cc. of absolute benzene. Thereby, 1,2-diisopropyl-hydrazine hydrochloride precipitated. The mixture was refluxed for one hour, then cooled to room temperature and filtered. The filtrate was concentrated in vacuo and the residue recrystallized from methanol. The 1-palmitoyl-1,2-diisopropyl-hydrazine thus obtained melted at 39°.

Example 4

A solution of 33.9 g. of chloroacetyl chloride in 200

cc. of absolute benzene was added dropwise, at room temperature and with stirring, to a solution of 70 g. of 1,2-diisopropyl-hydrazine in 1000 cc. of benzene. Thereby, 1,2-diisopropyl-hydrazine hydrochloride precipitated. The mixture was further stirred for some time, then permitted to stand for several hours and filtered by suction. The filtrate was washed with water, dried over sodium sulfate and concentrated in vacuo. The residue was purified by distillation in high vacuo. There was thus obtained 1-chloroacetyl-1,2-diisopropyl-hydrazine as a colorless viscous oil boiling at 67°/0.03 mm.

Example 5

A solution of 59 g. of 1,2-diisopropyl-hydrazine in 1300 cc. of absolute benzene was added dropwise, at room temperature and while stirring, to a solution of 35 g. of α -acetoxypropionic acid chloride in 200 cc. of absolute benzene. The mixture was stirred for an additional 1-2 hours and then permitted to stand overnight. The precipitated 1,2-diisopropyl-hydrazine hydrochloride was filtered by suction, the filtrate washed with water, dried over sodium sulfate and concentrated in vacuo. The oily residue which rapidly solidified was recrystallized from high boiling petroleum ether. The 1- α -acetoxypropionyl-1,2-diisopropyl-hydrazine obtained melted at 61-64°.

1 cc. of absolute methanolic 2 N sodium methylate solution was added to a solution of 10 g. of 1- α -acetoxypropionyl-1,2-diisopropyl-hydrazine in 50 cc. of absolute methanol. The mixture was allowed to stand overnight and then concentrated in vacuo. The oily residue was taken up in ether, the ethereal solution washed with a saturated sodium chloride solution, dried and concentrated. The oily residue rapidly solidified. Upon recrystallization from petroleum ether, the 1- α -hydroxypropionyl-1,2-diisopropyl-hydrazine obtained melted at 65-67°.

Example 6

A solution of 10.8 g. of methoxyacetyl chloride in 50 cc. of absolute benzene was added dropwise over a period of 2½ hours, at room temperature and while stirring, to a solution of 25.5 g. of 1,2-diisopropyl-hydrazine in 350 cc. of absolute benzene. Thereby, 1,2-diisopropyl-hydrazine hydrochloride precipitated. The mixture was stirred for an additional 4 hours at 40°, then cooled to room temperature and filtered. The filtrate was washed with a saturated sodium chloride solution and with a saturated sodium bicarbonate solution, dried over sodium sulfate and concentrated. The residue was purified by fractionating in vacuo. 1-methoxyacetyl-1,2-diisopropyl-hydrazine was thus obtained as a colorless oil boiling at 109-110°/12 mm.; $n_D^{22}=1.4525$; which solidified on standing at room temperature.

Example 7

16.2 g. of methoxyacetic acid anhydride and 25.5 g. of 1,2-diisopropyl-hydrazine were mixed together. Thereby, by cooling, the mixture was kept at a temperature below 50°. After 20 hours standing at room temperature, the methoxyacetic acid salt of 1,2-diisopropyl-hydrazine was precipitated. The slurry formed was distributed between ether and a saturated sodium chloride solution. The ethereal layer was separated, washed with a saturated sodium chloride solution and a saturated sodium bicarbonate solution, dried over sodium sulfate and concentrated. The residue was purified by distillation in vacuo. The colorless oil obtained at 109-110°/12 mm.; $n_D^{22}=1.4522$

consisted of 1-methoxyacetyl-1,2-diisopropyl-hydrazine. It solidified on standing at room temperature.

Example 8

A solution of 12.5 g. of methylmercaptoacetyl chloride in 100 cc. of benzene was added dropwise, while stirring, to a solution of 32 g. of 1,2-diisopropyl-hydrazine in 150

cc. of benzene. The mixture was refluxed for one hour, then cooled to room temperature and filtered. The filtrate was concentrated in vacuo and the residue purified by distillation. The 1-methylmercaptoacetyl-1,2-diisopropyl-hydrazine thus obtained boiled at 126-128°/12 mm.; $n_D^{22}=1.4855$.

Example 9

A solution of 10.5 g. of cyclopropanecarboxylic acid chloride in 100 cc. of absolute benzene was added dropwise, while stirring, to a solution of 32 g. of 1,2-diisopropyl-hydrazine in 150 cc. of absolute benzene. Thereby, 1,2-diisopropyl-hydrazine hydrochloride precipitated. The mixture was refluxed for one hour, then allowed to cool and filtered. The filtrate was concentrated and the residue purified by distillation in vacuo. The 1-cyclopropanecarbonyl-1,2-diisopropyl-hydrazine thus obtained boiled at 104-105°/13 mm.; $n_D^{23}=1.4640$.

Example 10

A solution of 14.6 g. of cyclohexanecarboxylic acid chloride in 50 cc. of absolute benzene was added dropwise over a period of 2½ hours, at room temperature and while stirring, to a solution of 25.5 g. of 1,2-diisopropyl-hydrazine in 450 cc. of absolute benzene. The mixture was stirred for an additional 4 hours at 40°, then cooled to room temperature and filtered. The filtrate was washed with a saturated sodium bicarbonate solution, dried over sodium sulfate and concentrated in vacuo. The residue was purified by distillation in vacuo. There was thus obtained 1-cyclohexanecarbonyl-1,2-diisopropyl-hydrazine as a colorless oil boiling at 65°/0.06 mm.; it solidified on standing at room temperature.

We claim:

1. A hydrazine derivative of the formula

wherein R represents a member of the group consisting of lower alkyl, higher straight chain alkyl having up to 17 carbon atoms, cycloalkyl groups having 3 to 6 carbon atoms, mono halo-lower alkyl, hydroxy-lower alkyl, lower alkanoyloxy-lower alkyl, lower alkoxy-lower alkyl and lower alkyl-mercapto-lower alkyl, and medicinally acceptable acid addition salts thereof.

2. A hydrazine derivative of the formula

3. 1-acetyl-1,2-diisopropyl-hydrazine.
4. 1-acetyl-1,2-diisopropyl-hydrazine hydrochloride.
5. 1-pivaloyl-1,2-diisopropyl-hydrazine.
6. 1-palmitoyl-1,2-diisopropyl-hydrazine.

7. A hydrazine derivative of the formula

8. 1-chloroacetyl-1,2-diisopropyl-hydrazine.
9. A hydrazine derivative of the formula

10. 1- α -acetoxypropionyl-1,2-diisopropyl-hydrazine.
11. A hydrazine derivative of the formula

12. 1- α -hydroxypropionyl-1,2-diisopropyl-hydrazine.
13. A hydrazine derivative of the formula

14. 1-methoxyacetyl-1,2-diisopropyl-hydrazine.
15. A hydrazine derivative of the formula

16. 1-methylmercaptoacetyl-1,2-diisopropyl-hydrazine.
 17. A hydrazine derivative of the formula

wherein the cycloalkyl group contains 3 to 6 carbon atoms.

18. 1-cyclopropanecarbonyl-1,2-diisopropyl-hydrazine.
 19. 1-cyclohexanecarbonyl-1,2-diisopropyl-hydrazine.
